AIR PUMP AND ALARM UNIT

Harry N. Eider, Youngstown, Ohio, assignor to
 "Automatic" Sprinkler Company of America,
 Youngstown, Ohio, a corporation of Delaware

Application August 10, 1940, Serial No. 352,086

4 Claims. (Cl. 230—111)

The principal object of this invention is the provision of a water powered air pump which will, when used in connection with a sprinkler system, serve to maintain suitable air pressure in the piping of the sprinkler system, or any system of air thermostats that might be used in connection therewith, as is desirable either for supervisory purposes or for holding closed either a mechanical or differential type control valve of the system.

A further object of the invention is the provision of a water powered air pump which will automatically maintain the air pressure in the piping of a sprinkler system between predetermined maximum and minimum pressures.

A further object of the invention is the provision of a water powered air pump incorporating means for maintaining a suitable air pressure in the piping of a sprinkler system during the intervals between periodic water powered operation of the pump.

A still further object of the invention is the provision of a pressure sensitive alarm unit which will, upon a given loss of pressure in the piping of a sprinkler system to which the same may be attached, serve to open a water valve and thus permit the energization of a water motor alarm or serve to close a switch of an electric alarm.

The water powered air pump and alarm unit is so constructed that either one or both of its operations may be utilized when connected with the piping of a sprinkler system as pressure responsive valves incorporated therein are duplicates, one controlling the introduction of water into the air pump portion of the device and the other controlling an alarm water valve positioned in a supply line connected with an alarm.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawings, wherein:

Figure 1 is a side elevation of the water powered air pump and alarm unit with parts broken away.

Figure 2 is a cross sectional view taken on lines 2—2 of Figure 1.

By referring to the drawings and Figure 1 in particular it will be seen that the pump and alarm unit comprises a body member 10 on either side of which there are positioned mechanism en-

closing housings 11 and 12 respectively which in turn are secured to the body member 10 by means of bolts 13 functioning through openings in the flanges 14 and 15 formed on the housings 11 and 12. The housings 11 and 12 are positioned over large openings in the body member 10. Positioned in these large openings are pressure responsive valve operative mechanisms one of which is shown in detail in Figure 2 in the right hand portion thereof.

By referring again to Figure 1 of the drawings it will be observed that the bottom of the body member 10 is provided with an opening in which is positioned a water leg 16 which is provided at its lower extremity with a cap 17 which in turn is provided with a plugged opening 18. Positioned vertically through the body member 10 and extending downwardly within the water leg 16 there is a secondary tubular water leg 19 which terminates short of the bottom of the water leg 16 and, as may be seen by referring to the uppermost portion of the illustration in Figure 1, emerges through an opening in the top of the body member 10 and is provided with an L 20 which forms an overflow passage for water rising upwardly through the secondary water leg 19. It is obvious that the delivery orifice of the L 20 may be connected to suitable piping leading to a suitable drain.

In order that water and air may be introduced into the body member 10 in order that the air pump action may take place, a jet pump chamber 21 is affixed by means of bolts 22 to one side of the body member 10 as may be seen in Figure 1, and by referring to Figure 2 and to the right hand portion thereof wherein a cross sectional detailed view of the jet pump is shown it will be seen that water entering by way of an orifice 23 is directed, at such times as a water control valve 24 is open, through a jet 25 and into a Venturi jet pump 26 by which action it causes a quantity of air to be delivered therewith into the body member 10 of the pump by way of an upwardly extending communication channel 27 which in turn forms a part of the jet pump housing 21 and is bolted to the body member 10 by bolts 22. Air is introduced into the Venturi jet pump through an orifice 28 in the bottom of the jet pump chamber 21. It will thus be observed that when the orifice 23 is connected to a suitable water supply source and the valve 24 is open, the resultant action of the water passing into the Venturi jet pump will be the introduction of a substantial quantity of air into the body member 10 along with the water. The water introduced will flow downwardly through

the water leg 16 which communicates with the bottom portion of the body member 10 and subsequently rise within the secondary water leg 19 to the uppermost end thereof of which is substantially above the body member 10 from which it will be discharged.

In order that the air introduced into the body member 10 may be retained so that a workable air pressure may be built up in the piping of a sprinkler system associated therewith by way of an opening 29, diaphragms 30 each of which carries a centrally positioned piston like structure 31 are positioned in the large openings between the body member 10 and the housings 11 and 12, the outer extremities of each of the diaphragms 30 being securely positioned between flange portions of the body member 10 and the flanges 14 and 15 of the housings 11 and 12. Thus air introduced into the body member 10 is restricted thereto by the flexible diaphragms 30 and their piston like structures 31 which form a flexible water and air tight seal.

It will thus be observed that when, due to the continuous operation of the Venturi jet pump, a satisfactory air pressure has been built up within the body member 10 of the pump and any associated piping of a sprinkler system, and any system of air thermostats that may be used in connection therewith, the normal tendency of the diaphragm 30 will be to move outwardly into the adjacent housing and in order that this movement may be suitably utilized to control the introduction of water into the Venturi jet pump, means has been associated with the diaphragm 30 and the water control valve 24 for either opening or closing the valve 24 in accordance with the position of the diaphragm 30 and its piston like structure 31 which in turn is adjustably opposed by a coil spring 32 with respect to a tubular adjustment member 33 which is threadably positioned in a threaded opening in the housing 12. The tubular adjustment member 33, threadably positioned in the opening in the housing 12, permits the tension on the spring 32 to be varied so that any desirable air pressure may be maintained within the body member 10. In order that the movement of the piston like structure 31 carried on the diaphragm 30 will result in movement of the water control valve 24, a rod 34 is affixed in an opening formed in a centrally located boss 35 on the piston like structure 31, and extends outwardly therefrom and terminates in a pivot structure 36 connected to an end of a secondary rod 37 which engages a part of the water control valve 24 by reason of an end thereof functioning within a suitable opening in the water control valve 24. The rod 37 is pivoted to an adjacent portion of the jet pump chamber 21 by a pivot 38. Immediately surrounding the rod 37 and the pivot 38 and forming a flexible water tight seal there is a diaphragm gland 39 which is positioned between a bracket 40 located within the housing 12 and a portion of the jet pump chamber 21 so that the rod 37 passes therethrough in a movable manner.

In order that the action of the water control valve 24 may be controlled and adjusted with respect to the air pressure built up within the body member 10 by the pump action, spring tensioned adjustment means have been provided to limit the movement of the rod 34, which is moved by the diaphragm 30 and its piston like structure 31, and comprises a pair of roller carrying arms 41 pivoted at 42 to a bracket 43 which is in turn affixed to the housing 12. The rollers carried on the roller arms 41 engage the rod 34 and, as 75

the rod 34 is provided with an irregular surface, tension brought to bear between the opposite ends of the roller arms 41 by means of an adjustably mounted spring 44 effectively controls the movement of the rod 34 until a desirable pressure against the diaphragm 30 has been established. The spring 44 is adjusted with respect to the roller arms 41 by means of an adjustment screw 45.

It will thus be observed that at such times as the air within the body member 10 reaches a pre-determined pressure the diaphragm 30 and the piston like structure 31 will sufficiently compress the spring 32, to enable the rods 34 and 37 to close the water control valve 24, and that when such action has taken place the water which has been overflowing through the L 20 on the upper end of the secondary water leg 19 will, as the air pressure within the body member 10 of the pump diminishes, drop within the secondary water leg 19 in direct relation thereto and thus serve to maintain the air pressure within the body member as the column of water rises in the water leg 16. This action continues until the water within the secondary water leg 19 has dropped to a level where it can no longer effectively move the column of water upwardly within the water leg 16. From this point on diminishing air pressure within the body member 10, as may be occasioned by leakage in the sprinkler system, results in the spring 32 moving the diaphragm 30 and the piston like structure 31 into the body member 10 and thus effectively opening the water control valve 24 which completes the cycle of operation. It will thus be seen that the action of this water powered air pump is entirely automatic and that due to the dual water leg construction the air pressure developed by the pump is maintained satisfactorily during the intervals between the actual pumping periods.

In order that an alarm may be given upon the loss of supervisory air in the sprinkler system, a duplicate mechanical assembly comprising a diaphragm and the piston like structure supported thereby is positioned on the opposite side of the body member 10 and within the housing 11 so that upon the continuous rapid reduction of air pressure within the body member 10 the duplicate diaphragm and associated mechanism serves to open an alarm water valve 46 which is positioned in a supply line normally supplying a water motor alarm or communicating with an electrical alarm switch, the outlet to the alarm mechanism being indicated by the numeral 47. The alarm water valve 46 is controlled by and connected to a diaphragm assembly exactly the same as that heretofore described in connection with the water control valve 24 which controls the jet pump assembly and for the purposes of simplicity has not been illustrated in the drawings. Suitable rods comparable in exact detail to the mechanism heretofore described connect the diaphragm with the alarm water valve 46 and are indicated in the drawings by the numerals 48 and 49, the rod 49 being pivoted at a point 50 and passing through a flexible diaphragm gland 51 similar in all respects to the construction heretofore described. The alarm water valve assembly is, like the jet pump chamber assembly 21, bolted to the body member 10 by means of bolts 52.

It will be obvious that in the event that a pumping action only is desired the device may be constructed so as to incorporate only the jet pump and affiliated controlling portions of

the pump and other means would be utilized for the energizing of an alarm to indicate the loss of supervisory air pressure from the sprinkler system to which the pump was affixed. By the same token it may be found desirable to construct the device so as to include only the alarm valve portion thereof which would be utilized in connection with a sprinkler system, the air pressure in which was supplied and maintained by other means. It is thus evident that changes in the precise structure as shown and described herein are not only possible but desirable. In operation the alarm portion of the device is adjusted so that the alarm water valve 46 opens at such times as the air pressure in the body 15 member 10 and associated piping of a sprinkler system falls and continues to fall until a predetermined point has been reached.

What I claim is:

1. In a water actuated air pump having a hollow body member, an opening in the said hollow body member, a water actuated air injector in communication with the said hollow body member, a water valve associated with the said injector, pressure responsive means responsive to either an increase or decrease of pressure within the said hollow body member for controlling the admission of water to the said water actuated air injector, said means comprising a sleeve positioned in the said opening and extending inwardly therefrom, a piston telescopically engaging said sleeve, an annular flexible member affixed to the said piston and to the said hollow body member so as to form a water tight seal therebetween, levers connecting the said piston and the said water valve and means associated with the said levers for limiting the movement thereof to a snap like action at such time as air within the hollow body member reaches a predetermined pressure as determined by the said limiting means, and means including a vertically positioned water column forming an air seal for conducting the water away from the said body member.

2. In a water actuated air pump having a hollow body member, an opening in the said hollow body member, a water actuated air injector in communication with the said hollow body member, a water valve associated with the said injector, pressure responsive means responsive to either an increase or decrease of pressure within the said hollow body member for controlling the admission of water to the said water actuated air injector, said means comprising a sleeve adjustably positioned in the said opening and extending inwardly therefrom, a piston telescopically engaging said sleeve, a spring positioned between the said sleeve and the said piston, an annular flexible member affixed to the said piston and to the said hollow body member so as to form a water tight seal therebetween, levers connecting the said piston and the said water valve and means associated with the said levers for limiting the movement thereof to a snap like action at such time as air within the hollow body member reaches a predetermined pressure as determined

by the said spring, and means including a vertically positioned water column forming an air seal for conducting the water away from the said body member.

5 3. In a water actuated air pump having a hollow body member, an opening in the said hollow body member, a water actuated air injector in communication with the said hollow body member, a water valve associated with the said injector, pressure responsive means responsive to either an increase or decrease of pressure within the said hollow body member for controlling the admission of water to the said water actuated air injector, said means comprising a sleeve positioned in the said opening and extending inwardly therefrom, a piston telescopically engaging said sleeve, an annular flexible member affixed to the said piston and to the said hollow body member so as to form a water tight seal therebetween, levers connecting the said piston and the said water valve, one of the said levers having an irregular surface, and means associated with the said irregular surfaced lever for limiting the movement thereof to a snap like action at such time as air within the hollow body member reaches a predetermined pressure, said means comprising a pair of spring pressed rollers engaging the said irregular surfaced lever, the said irregular surfaced lever adapted to move between the said rollers, and means including a vertically positioned water column forming an air seal for conducting the water away from the said body member.

20 4. In a water actuated air pump having a hollow body member, an opening in the said hollow body member, a water actuated air injector in communication with the said hollow body member, a water valve associated with the said injector, pressure responsive means responsive to either an increase or decrease of pressure within the said hollow body member for controlling the admission of water to the said water actuated air injector, said means comprising a sleeve 25 adjustably positioned in the said opening and extending inwardly therefrom, a piston telescopically engaging said sleeve, a spring positioned between the said sleeve and the said piston, an annular flexible member affixed to the said piston and to the said hollow body member so as to form a water tight seal therebetween, levers connecting the said piston and the said water valve, one of said levers having an irregular surface, and means associated with the said irregular surfaced lever for limiting the movement thereof, and the water valve, to a snap like action at such time as air within the hollow body member reaches a predetermined pressure as determined by the said adjustably mounted spring, said means comprising a pair of spring pressed rollers engaging the said irregular surfaced lever, the said irregular surfaced lever adapted to move between the said rollers, and means including a vertically positioned water column forming an air seal for conducting the water away from the said body member.

25 50 55 60 65 HARRY N. RIDER.
